MECHANICAL LEAD PENCIL

Filed June 22, 1936

UNITED STATES PATENT OFFICE

2,164,166

MECHANICAL LEAD PENCIL

Max Schaefer, Bloomfield, N. J., assignor to
Eagle Pencil Company, New York, N. Y., a cor-
poration of Delaware

Application June 22, 1936, Serial No. 86,565

5 Claims. (Cl. 120—18)

My present invention relates to mechanical pencils, more especially to pencils of the type including an expel movement, that is, a movement for ejecting the short substantially useless stub 5 of lead that blocks insertion of a fresh lead.

As conducive to a clear understanding of the invention, it is noted that many otherwise satisfactory known mechanical pencils have the limitation that the expel movement thereof has an 10 effective stroke inherently so short that were the writing lead clutched through a sufficient length to assure uniform effectiveness of hold, the length of expel stroke would be inadequate to perform its function.

15 Among the objects of the present invention are to provide a mechanical pencil of the above type in which the expel movement has a stroke of increased length to permit effective ejection of a relatively longer and securely clutched lead extremity, and more particularly to attain the result by a relatively slight modification of known 20 structures, without the introduction of added elements or added manufacturing cost and without in any way detracting from the effectiveness 25 of otherwise known and approved constructions.

In the accompanying drawings in which are shown one or more of various possible embodiments of the several features of the invention,

Fig. 1 is a view in longitudinal cross-section of 30 a desirable embodiment of the invention,

Figs. 2, 3, 4 and 5 are fragmentary sectional views illustrating successive stages in the operation of the expel movement of the pencil,

Figs. 6 and 7 are transverse sectional views on 35 a larger scale taken respectively on the lines 6—6 and 7—7 of Fig. 1,

Fig. 8 is a perspective fragmentary view on a still larger scale showing the modified lead tube structure, and,

Fig. 9 is a perspective view on a like scale showing 40 the clutch tube and eject plunger combination.

The accompanying drawing shows an application of the invention to that general type of mechanical lead pencil described in greater detail in the prior patent to Isidor Chesler, No. 1,956,271 granted April 24, 1934. For a clearer understanding of the invention, the general assembly disclosed in said patent will be briefly set forth, it being understood that the invention has a wider range of application within the scope of the appended claims.

Referring now to the drawing, there is shown a pencil case 10, illustratively of molded material 55 having its axial bore molded as a helical track or

feed thread 11 and having molded into the forward reduced point end thereof a metal ferrule 12.

Extending longitudinally of the case and desirably contacting at its forward end the inner 5 end of the ferrule 12 is a longitudinal lead tube 13 which rides in the bore of the case and is longitudinally slotted to present edges 14 and 15. The lead tube may be bifurcated at its upper end, with legs 16 bent over to overlap the upper end 10 of the case to be keyed into the eraser ferrule 17 telescoped over said end of the case and rotatable thereon to operate the lead moving mechanism.

A lead propeller shown as a clutch sleeve 18 is 15 slidably mounted in the lead tube. The forward end of the propeller here serves as a clutch 19 to grip the rear end or stub of the writing lead 20. The clutch tube 18 may be made from a blank 20 with its longitudinal edges contacting and affording integral lugs 21 on which is preferably mounted the low friction roller 22 to ride in feed track 11.

The expel mechanism comprises an expel 25 plunger or pin 23 extending into the rear end of the lead clutch sleeve 18 and is preferably materially longer than the clutch tube. It has a flattened extension 24 affording a shoulder 25 to limit the advance thereof into sleeve 18 and an integral lateral lug 26 to ride in the feed track 11. 30

According to the present invention, the slot 14—15 of the lead tube leads into a modified conformation at the forward end of said tube which presents an edge extending at an angle relative to said slot and leads to a pointed extremity 27 of 35 the lead tube.

While the front edge conformation joining the extremity 28 of slot edge 15 to the advanced point 27 of the other slot edge 14 may be helical from end to end, and such structure comes within the scope of the invention as claimed, it is advantageous to use the modification of such construction now to be described. As shown, the end edge of the tube 13 extends substantially peripherally at 29 for approximately half the circumference from the forward extremity 28 of slot edge 15 and there merges into helical edge 30 leading for approximately a half turn to the advanced point 27. 40

In the course of feed operation, the roller or lug 22 on the clutch 18 in time approaches the end 28 of the shorter slot edge 15 as shown in Fig. 2. After the lug 22 of the clutch has passed the end 28 of slot edge 15, the further rotation of lead tube 13 through substantially a half turn occurs 45 50 55

without longitudinally advancing or otherwise moving the clutch tube lug 22, since the transverse forward edge 20 of the lead tube rides thereover. This stage of the operation is shown in Fig. 3. In further rotation, the lug 22 of the clutch is pushed by the helical edge 30 of the lead tube 13 as shown in Fig. 4, to resume its longitudinal advance, but at rate considerably retarded as compared with the rate of advance effected where the pushing edge or slot extends longitudinally. Finally, as shown in Fig. 5 the lug 22 has bottomed against the metal ferrule 12 and can proceed no farther, in which position it has also reached the point extremity 21 of the lead tube 13.

As also appears in Fig. 5, the eject plunger or pin 23 protrudes materially beyond the clutching end of the clutch tube 13 when it reaches the extremity of its eject stroke, thereby to assure effective clearing of the clutch tube of any particles of lead and to give a clearly visible indication to the user that the lead stub has in fact been completely removed.

It is seen that in the travel of lug 22 from the position shown in Fig. 2 to that shown in Fig. 5, a slippage of practically a complete turn of the lead tube 13 relative to the lug 22 has occurred. No such slippage of the ejector plunger 23 has, however, taken place, since its lug 26 has throughout remained confined by slot 14—15 of the lead tube 13. During this action, therefore, the ejector plunger or pin 23 has advanced within the clutch tube through a range substantially equal to the full pitch of the feed track or screw 11, which in a desirable construction is equal to 0.2 inch. Accordingly, it is possible and is preferred to clutch within the lower extremity of the clutch tube 13 a length of lead of 0.140 inch which is quite effective for secure hold, as compared to the much lesser clutched length used where only a short stroke of eject movement is available.

The eject action it is seen, occurs in two stages, in one of which the clutch lug 22 does not advance at all during a partial rotation of the lead tube and in the final step of which it does advance but at a rate retarded as compared with that of the eject pin lug 26. The eject mechanism is, accordingly, effectively started to dislodge the lead stub by complete stoppage of the clutch tube and application of the complete propulsive force for advance of the ejector plunger. After the stub has thus been loosened the expel action is completed, though more gradually, the expel plunger advancing relative to the more slowly advancing clutch.

By the simple arrangement set forth for bringing about the enhanced stroke of eject movement, the lead tube is not weakened because the protruding generally triangular tongue 31 has considerable mechanical strength in view of its longitudinal stiffening curvature, strength more than adequate to propel the low friction roller lug 22 used in the construction shown and even to propel lugs of other types that impose considerably more friction.

Having thus described my invention, what I claim as new and desire to secure by Letters Patent of the United States is:

1. A mechanical pencil comprising a case having a helical feed thread therein and rigid therewith, a rotatable longitudinally slotted lead tube in said case, a lead propeller tube in said lead tube having a lug protruding through said slot into the feed thread, a lead expel pin in said propeller tube having a lug also protruding through

the slot of said lead tube into said feed thread, said lead tube being obliquely cut away at its forward end from one side of the longitudinal slot to the forward extremity at the other side of the longitudinal slot to afford room for nearly a complete rotation of the lug on the lead propeller after the latter has reached the extremity of its confined course along the lead tube slot, thereby to permit a substantial advance of the lug on the expel pin.

2. A mechanical pencil comprising a case having a feed thread therein and rigid therewith, a longitudinally slotted lead tube lodged in said case and rotatable from the rear end thereof, a lead propelling clutch member longitudinally slidable in said lead tube and having a lug extending through the slot of said lead tube into the feed thread, an expel member having a pin to abut the lead in said clutch and having a lug extending through the slot of said lead tube into said feed thread and trailing behind the lug on said clutch member, means near the forward end of the case to limit the further longitudinal advance of the clutch tube lug, said lead tube having an inclined forward edge terminating substantially at a point and admitting of rotation of the clutch tube lug for nearly a complete turn relative to said lead tube, whereby a substantial advance of the lug of the expel member is permitted for effective expulsion of a substantial length of lead effectively clutched.

3. A mechanical pencil comprising a case having longitudinally thereof and rigid therewith a feed thread, a longitudinally slotted lead tube in said case, terminating near the forward end thereof, a lead propeller in said lead tube having means at its forward end for clutching the rear end of a writing lead and having a lug protruding through the slot of said lead tube and riding in said feed thread, a lead expel pin in said lead propeller and having a lug protruding through the slot of said lead tube into said feed thread to trail the lug on said lead propeller, the forward end of said lead tube having a lug guide conformation continuous with one of the edges of the longitudinal slot thereof, and leading to a point at the forward extremity of the lead tube and permitting slip of the lead propeller lug through nearly a complete revolution relative to the lead tube after the clutch lug passes the lower extremity of the longitudinal slot of the lead tube.

4. A mechanical pencil comprising a case having longitudinally thereof and rigid therewith a feed thread, a longitudinally slotted lead tube extending substantially the length of said pencil and rotatable from the rear end thereof, said tube terminating near the point of said pencil, a lead clutch tube in said lead tube having means at its forward end for gripping the rear end of the writing lead and having a lug protruding through the slot of said lead tube and riding in said feed thread, a lead expel pin in said lead clutch tube having a lug protruding through the slot of said lead tube into said feed thread to trail the lug of said clutch tube, the forward end of said slotted lead tube having one side of the longitudinal slot thereof terminating at an advanced point on said tube materially beyond the other edge of said slot, the forward edge of said lead tube beyond the latter edge of the slot thereof presenting an inclined surface determining a helically directed edge from the forward point, merging with a generally semi-circular square-

ended edge leading to the inner edge of the longitudinal slot.

5. In a mechanical pencil of the propel-eject type, comprising a case having a lead feeding means, a movable lead holding clutch coacting with said lead feeding means, a movable eject plunger also coacting with said lead feeding means, and movable in synchronism with said clutch through substantially its entire course but 10 automatically advanced relative thereto to perform its eject action when the clutch approaches the forward end of its course; the combination

therewith of means for continuing the forward propulsion of the eject plunger, while interrupting that of said clutch near the forward end of the stroke thereof, for loosening a lead stub lodged in said clutch and means for thereupon resuming the longitudinal advance of the clutch to the extremity of its course, at a rate retarded relative to that of the continued advance of the eject plunger for final expulsion of such lead stub.
